US00D873289S

(12) **United States Design Patent** (10) **Patent No.:** **US D873,289 S**
(45) **Date of Patent:** **** Jan. 21, 2020**

(54) **DISPLAY SCREEN OR PORTION THEREOF WITH GRAPHICAL USER INTERFACE**

(71) Applicants: **Saphyre, Inc.**, Hoboken, NJ (US); **Gabino M. Roche, Jr.**, Hoboken, NJ (US)

(72) Inventors: **Gabino M. Roche, Jr.**, Hoboken, NJ (US); **Kelly Downing**, Boston, MA (US)

(73) Assignees: **Saphyre, Inc.**, Hoboken, NJ (US); **Gabino M. Roche, Jr.**, Hoboken, NJ (US)

(**) Term: **15 Years**

(21) Appl. No.: **29/676,417**

(22) Filed: **Jan. 10, 2019**

(57) **CLAIM**

An ornamental design for a display screen or a portion thereof with a graphical user interface, as shown and described.

DESCRIPTION

The sole FIGURE is a front view of a display screen or a portion thereof with a graphical user interface.

The outermost broken-line rectangle illustrates the perimeter of a display screen or portion thereof and forms no part of the claimed design. The remaining broken lines illustrate portions of a graphical user interface and form no part of the claimed design.
